UNITED STATES PATENT OFFICE.

FREDERICK WILLIAM GRELL, OF NEW YORK, N. Y.

DESIGN FOR A COMB.

SPECIFICATION forming part of Design No. 33,574, dated November 20, 1900.

Application filed June 12, 1900. Serial No. 20,078. Term of patent 14 years.

To all whom it may concern:

Be it known that I, FREDERICK WILLIAM GRELL, a citizen of the United States, residing at College Point, county of Queens, and 5 State of New York, have invented and produced a new and original Design for Combs, of which the following is a specification.

My invention relates to a design for combs. I will describe a comb embodying my invention.

In the accompanying drawings, Figure 1 is a front view of a comb embodying my invention. Fig. 2 is an edge view.

A represents the body of the comb, and a 5 the teeth, which are provided along the opposite longitudinal edges of the body. The leading or essential feature of my design consists in the body of a comb having a compound

curve transversely of its length. In the drawings I have shown the body as being in the 20 form of a reverse curve. The longitudinal middle portion of the body is thicker than the longitudinal edges of the body, there being a taper transversely from the said middle portion to the said edges. 25

What I claim as my invention is—

The design for a comb substantially as shown and described.

In testimony whereof I have signed my name to this specification in the presence of 30 two subscribing witnesses.

FREDERICK WILLIAM GRELL.

Witnesses:

ARTHUR GRELL,
WILLIAM HOLLWEG.
